UNITED STATES PATENT OFFICE.

JOHN KOPECKY, OF MASON CITY, IOWA.

CHANGE-HANDLING DEVICE.

1,372,356.

Specification of Letters Patent. Patented Mar. 22, 1921.

Application filed March 4, 1920. Serial No. 363,305.

To all whom it may concern:

Be it known that I, JOHN KOPECKY, a citizen of the United States, residing at Mason City, in the county of Cerro Gordo and State of Iowa, have invented certain new and useful Improvements in Change-Handling Devices, of which the following is a specification.

This invention relates to the coin-holding art and has for its object the provision of a device adapted for use in banks, stores, or any place where money is handled and change made, whereby change in the form of coins may be readily delivered into the hand of a person, thereby obviating the tedious process of picking up the coins from the counter.

An important and more specific object is the provision of a device of this character in the form of an open ended box having a pivoted platform in its top upon which the coins are deposited, the platform carrying a depending weight for holding it in normal position and movable by the fingers of a hand inserted into either end of the device whereby to tilt the platform and cause coins thereon to slide off into the hand.

An additional object is the provision of a device of this character which will be simple and inexpensive in manufacture, highly efficient in use, neat and attractive in appearance, durable in service, and a general improvement in the art.

With the above and other objects and advantages in view, the invention consists in the details of construction to be hereinafter more fully described and claimed, and illustrated in the accompanying drawings in which—

40 Figure 1 is a plan view,

Fig. 2 is a central longitudinal sectional view,

Fig. 3 is a central cross sectional view, and

45 Fig. 4 is a plan view showing a slightly modified form.

Referring more particularly to the drawings, the numeral 10 designates a casing of box-like formation, open at both ends. This 50 casing may be constructed of any suitable material, ordinarily metal, but if desired, might be formed of glass. The top 11 of this casing is provided centrally with an opening 12 which may be of any desired 55 shape but which may conveniently be rectangular, as shown in Fig. 1. Secured

within this opening is a guard flange 13 formed as a strip secured in place by any suitable means and this flange extends above and below the top 11, as shown. 60

Disposed within the confines of the guard flange 13 is a tray or platform 14 which is formed preferably of metal and which is of a size to fit snugly within the confines of the guard without binding. Upon this 65 tray is mounted a depending plate 15 formed with lugs 16 secured to the tray. This plate extends transversely of the casing and has its upper corners formed with trunnions 17 journaled through the sides 70 of the casing whereby the tray and plate will be pivotally mounted as a unit. Adjacent the plate the lower portions of the flanges 13 are cut away to provide shoulders 18 engageable by the plate for limiting movement thereof. 75

The plate 15 provides means whereby the tray or platform may be moved, and to facilitate the manipulation, the plate is formed with or carries a weight 19 provided 80 on its opposite sides with concavities 20.

In the operation of the device the person making change places the coins upon the tray or platform 14, the guard flange 13 preventing them from slipping off. The tray 85 is preferably concave so that coins placed thereon will tend to dispose themselves at the center. The person to receive the change inserts his hand through the open end of the casing 10 and engages his fingers 90 against the concavity or depression 20 in the weight 19 and presses against the weight which will result in movement of the parts into the position shown by dotted lines in Fig. 2. As the tray is thus tilted it will be 95 apparent that the coins thereon will slide off into the palm of the person receiving the change. When the hand is then removed the weight 19 will return the tray to normal position. It is preferable, though not necessary, that the ends of the casing 10 be cut away, as shown at 21, so that the hand may be more easily inserted without engaging against the edge. It will be obvious that both ends of the device are the same so 105 that an error being made in making change the person making the change may insert his hand within his end of the casing and recover the coins. 110

In Fig. 4 I have shown a slightly modified form. In this form the structure is the same except that the guard flange 13^a

and tray 14^a are of different shape, the ends being rounded instead of straight. In this form the top 11^a is intended to be made of metal having glass panels 22 inserted therein adjacent the ends. The operation of this form is of course the same as that of the other form.

While I have shown and described the preferred embodiments of my invention, it will of course be understood that I reserve the right to make such changes in the form, construction, and arrangement of parts as will not depart from the spirit of the invention or the scope of the subjoined claims.

Having thus described my invention, I claim:

1. A device of the character described comprising an open ended casing provided in its top with an opening, a guard flange surrounding said opening, a platform pivoted within and filling said opening, a plate

secured to and depending from said platform, and a weight on said plate, said weight being provided at opposite sides with finger engaging depressions.

25

2. A device of the character described comprising an open ended casing provided in its top with an opening, a guard flange within said opening and extending above and below the top, a platform disposed within the confines of said flange, a plate secured to and depending from said platform at its center, trunnions on the upper corners of said plate journaled within the sides of the casing, said plates being 30 weighted, and said flange below the top being cut away adjacent the plate and engageable thereby to limit swinging movement thereof.

In testimony whereof I hereto affix my 40 signature.

JOHN KOPECKY.
